UNITED STATES PATENT OFFICE.

GEORGE B. LOUDERBACK, OF COMPTON, CALIFORNIA.

DRILLING BIT.

Application filed February 11, 1924. Serial No. 691,998.

To all whom it may concern:

Be it known that I, GEORGE B. LOUDERBACK, a citizen of the United States, residing at Compton, in the county of Los Angeles and State of California, have invented a new and useful Drilling Bit, of which a specification is set forth below.

In this specification, and the accompanying drawing, I shall describe and show a 10 preferred form of my invention, and specifically mention certain of its more important objects. I do not limit myself to the forms disclosed, since various changes and adaptations may be made therein without departing from the essence of my invention as hereinafter claimed; and objects and advantages, other than those specifically mentioned, are included within its scope.

My invention relates to well drilling bits 20 for use with rotary rigs. Its principal objects include; first, to provide a tool of this character having extensible cutting blades adapted for being periodically advanced as they become worn, without removing the bit 25 from the drill hole; second, to afford facilities for advancing the cutting blades, while underground, in such a manner that the gauge of the drill hole may constantly be maintained, or even enlarged; and, third, to 30 accomplish the above objects by means of a relatively simple construction that may be depended upon to function as intended.

These objects are accomplished by means of the construction illustrated in the accompanying drawings, in which—

Figure 1 is a longitudinal axial section of the upper portion of the tool in elevation;

Figure 2 is a similar section of the lower portion of the tool, taken on the same plane 40 as Fig. 1;

Figure 3 is a longitudinal axial section of the upper portion of the tool taken on a plane revolved 90 degrees from that of the first two figures;

Figure 4 is a similar section of the lower portion of the tool, taken on the same plane as Fig. 3;

Figure 5 is a much enlarged perspective 50 view of an upper portion of the operating mechanism;

Figure 6 is an enlarged axial section of the lower portion of the operating mechanism, taken on the same plane as Fig. 3, and

Figures 7, 8, 9, and 10 respectively are 55 cross sections taken on the lines 7—7, 8—8, 9—9, and 10—10 of Figs. 1 and 2.

Similar reference numerals refer to similar parts throughout the several views.

In a general way my improved tool is 60 adapted to operate in the manner of the ordinary fish-tail bit employed in rotary drilling, there being a pair of cutting blades, in substantially the same plane, extending oppositely from the axis. The leading bottom edges of these blades do the cutting. In all such tools the wear on the cutting edges tends to become greater as the distance from the axis increases, due to the greater 70 cutting speed and the greater amount of material encountered. In addition to this the tips have the additional duty of maintaining the gauge of the drill hole and have to withstand the abrasion caused by the unavoidable wobbling of the tool. In consequence of this the tips of ordinary bits soon become rounded and blunt, and the tool is thereby rendered unfit for further service until it has been withdrawn from the drill 75 hole and redressed.

Obviously, in the case of deep wells particularly, the time lost in the repeated withdrawals and re-placement of ordinary bits is often a matter of grave concern. Moreover, as the tips of the cutting edges of 80 such bits become rounded by wear, the drill hole loses its gauge and becomes smaller. Consequently, when a redressed tool of standard gauge is substituted; it has to perform a reaming operation before the bottom of the 85 hole is reached. This reaming duty comes entirely upon the tips of the blades and in a large measure destroys their cutting efficiency before the depth drilling can be resumed.

In a previous application for patent, filed January 16, 1924, Serial #686,569, I disclosed a novel type and arrangement of cutting blades, and means for advancing them 90 from the lower end of the tool obliquely to 100

the axis. Entirely similar blades and blade arrangement are employed in the tool to be described, but are not claimed herein per se. The means employed for advancing the blades in the present case are, however, quite distinctive and constitute the present invention.

The adjustable cutting blades 11 and 12 are bifurcated and provided with a flange 13 on their leading faces at each side of their bifurcations. A thicker flange 14 is provided at the leading side of their outer edges. It is now possible to make these flanges, as well as the whole leading faces of the blades, very hard in comparison to the main body of metal. The cutting edges therefore have a greater wear-resisting quality and, for that reason, the blades have a marked self-sharpening tendency. This tendency is further enhanced by the fact that the blades are relatively very thin, but strength is not sacrificed since they are backed up and supported, close to their cutting edges, by the heavy metal of the tool body. The localized thickening of the blades by the flanges, where the greatest tendency to wear occurs, tends to make the wear on the cutting edges more uniform and thus to prolong their effective drilling life.

This ability to advance the cutting blades obliquely to the axis, provided the cutting edges have not been destroyed, makes the tool very largely independent of the shape to which the blades may wear. Thus, in the event that the points of the blades become rounded, the gauge of the drill hole can be maintained by advancing the blades, and the tool will continue to cut as effectively as it did before the rounding occurred.

It will occur to some that, as the blades are obliquely advanced from the end of the tool, the cutting edges will recede from the center; and that, in the form depicted, there are in fact no cutting edges at the center of the tool. It is conceivable that in certain formations, with a perfectly centered revolving tool, this disposition of the cutting edges might tend to leave a central core that would interfere with the drilling. In practice, however, this never occurs. The tool never revolves truly about a fixed axis, and the unavoidable wobbling prevents the formation of such a core, since it would be quickly cut into and destroyed if it occurred. Furthermore, the weight of the tool string, which is very heavy, could not be supported by a core of this kind. It would quickly crumble under such a load. For those reasons no trouble from cores is ever experienced in drilling operations of this character.

The body of my bit is made in semi-cylindrical halves 15 and 16, of identical shape, with accurately machined or ground faces.

These are cast or forged with various re-

cesses such as 17, for the accommodation of the working parts they are to enclose, and are assembled face to face my means of a threaded ring 18 at the top, and a wedge band 19 at the lower end. The lower portion of the body is slightly wedge-shaped, as indicated in Fig. 4, and is a modified ellipse in section, as shown in Fig. 10. This portion becomes increasingly elongated in cross section towards the lower end of the tool. Wedge band 19 is driven from the bottom on to a slightly tapered seat against a shoulder at 20. Bolts 21, passing through the bifurcations of the cutting blades, afford still further security against displacement of the body halves.

The central portion of the tool body is threaded at 22 and a tubular housing 23 is screwed upon it at that point. This housing is somewhat enlarged at its upper end and a tubular member 24 is screwed into the top. Member 24 carries an integral taper-threaded "pin" 25 at its upper extremity, for engagement by the "tool joints" of the tool string.

The mechanism by which the cutting blades are held and controlled is mostly enclosed within housing 23 and the halves of the tool body. It comprises a relatively long feed screw 26 engaged by a cylindrical flanged nut 27. The screw itself does not turn. It is lowered by turning its feed nut, which may be revolved but is longitudinally positioned by means of its flanges 28 which engage corresponding grooves in the body parts.

At the lower end of the feed screw is a flattened blade retainer 29 having a transverse groove 30 across each of its faces adjacent to the bottom edge. The two cutting blades are similarly grooved to form flanges at their top ends, the end flanges of the blades being adapted to fit into the grooves of the retainer and vice versa. The cutting blades are engaged by the retainer in this manner and are prevented from disengaging by the shallowness of the recess 17 in which they work. As the blades are fed obliquely outward from the end of the tool by lowering the feed screw, their upper ends necessarily are constrained to slide transversely across the blade retainer, and this is permitted by the method of engaging just described.

It should be noted at this point that the angularity of the cutting blades 11 and 12, with respect to the tool body, is maintained at all times by means of oblique grooves in the body in which flanges 13 and 14 of the blades are slidingly engaged. This is clearly illustrated in Fig. 10 and indicated by dotted lines in Fig. 2.

Feed nut 27 is turned to lower the feed screw by means of a ratchet clutch device. This comprises an operating spool 31 with

a smooth bore, through which the feed screw passes. The adjacent end faces of the feed nut and operating spool have radial ratchet teeth 32, adapted for mutual engagement.

5 Operating spool 31 has a multiple thread 33 on its outer surface adapted to engage a toothed nut 34. Beneath this nut is a light helical spring 35 supported at the bottom by a ball thrust bearing 36.

10 The upper portion of the operating spool is provided with a longitudinal key-way 37 and is surrounded by the tubular end of the driving quill 38. This quill has an internal longitudinal key 39, engaging key-way 37 in the operating spool, and the latter is adapted to slide longitudinally within the quill and to be rotated by it in any position, through the key and key-way. The upper end of the quill is smooth-bored to permit 20 the operating screw to pass freely through it, and is provided with peripheral teeth 40 whereby it may be driven.

In order to operate the feed mechanism just described friction drive devices are located in the upper end of housing 23. These comprise a pair of diametrically opposed friction rollers 41 rotatably mounted in power blocks 42 which are adapted to slide radially in and out of rectangular orifices 30 cut for that purpose in the enlarged upper end of housing 23. The power blocks are normally separated by compression springs 43, so as to re-act against each other and to force their respective friction rollers into 35 contact with the internal walls of the well casing. Revolving the tool will then cause the rollers to revolve about their individual axes and furnish a source of power for operating the feed mechanism.

40 Reduction gearing, indicated at 44, is located within each of the power blocks and the power taken from the rollers is communicated to drive shafts 45 through telescopic joints 46 and universal couplings 47. 45 At the lower ends of drive shafts 45 are pinions 48 meshing with teeth 40 of the driving quill.

Control of the feeding mechanism is accomplished through an offset plunger rod 50 at each side of the cutting blades. These are adapted to slide longitudinally in slots in the tool body, and extend from the bottom of the tool nearly to its top. At their upper ends the plunger rods are connected by a yoke bar 50 and they are normally pressed downward and outward from the end of the tool, by a compression spring 51 re-acting against this yoke. At their lower ends the plunger rods are fixed to an operating shoe 52.

Power blocks 42 are provided with upwardly pointing wedge shaped grooves 53 in each of their lateral faces. Corresponding wedge shaped flanges 54 are provided 65 in a pair of sliding cams 55 fixed at the

proper points to the respective plunger rods. Flanges 54 are adapted to engage grooves 53 to force the power blocks together when the cams are raised by the plunger rods. In this manner, when the weight of the tool 70 is allowed to rest upon shoe 52, the plunger rods and cams are pushed upward and bring the power blocks together. Conversely when the weight of the tool is taken off shoe 52 the rods and cams are pushed downward by spring 51 and the power blocks are forced outward by springs 43 until the friction rollers are in contact with the well casing. Rotating the tool in this position will then operate the feed mechanism to advance 80 the cutting blades from its lower end.

I have provided in my improved bit a means whereby a definitely pre-determined number of turns may be imparted to the feed nut in the manner just described. Operation of the feed-driving mechanism beyond this point will cause ratchet teeth 32 to disengage and prevent over-feeding of the cutting blades through careless operation. The construction of this feed-limiting 90 mechanism has already been described in part. Its operation is as follows:

On plunger rods 49 are splines 56 adapted to engage the teeth of nut 34 to prevent its being turned. This engagement takes place 95 as soon as the weight of the tool is taken off the operating shoe and the plunger rods are pressed downward by spring 51. The feeding mechanism is then in position to operate as soon as power is applied to it, 100 and operating spool 31 is turned to lower the feed screw and nut 34 is forced downward by the action of multiple thread 33. When nut 34 has traveled downward as far as it can go by reason of its reaching 105 stops 57, the further rotation of the operating spool will result in raising the latter and causing ratchet teeth 32 to become disengaged. The toothed nut is restored to 110 its normal position by reversing the rotation of the tool while in its raised position.

Beneath feed nut 27 it is desirable to install a ball thrust bearing 58 to reduce the frictional resistance of this nut when it is being turned. At that time the weight of the cutting blades is hung upon the feed screw and is supported by this thrust bearing.

An important feature of my device remaining to be described is the manner in which circulating water is delivered in advance of the cutting edges of the blades. Within the upper portions of the body halves circulating water grooves are provided and are closed to form tight water courses when the halves are assembled. A pair of smaller holes 59 are drilled from the bottom of each half to communicate with the respective lower ends of these water courses. These small holes 59 are located 125 about as indicated in Fig. 10, just forward 130

of the cutting edges of the blades, and in a position to deliver the circulating water most advantageously.

When the body halves are assembled, pipes 60 are brazed, or otherwise tightly jointed, into the upper ends of the water circulating grooves in the body parts, and a distributing box 61 is mounted upon the upper ends of these pipes in the manner indicated in Figs. 1 and 3. This box has a central inlet pipe 62 adapted to pass through an axial bore in pin 25, and be made tight therein by a stuffing box such as is indicated in Fig. 3 at 63.

15 The construction and operation of the essential elements of my invention will be clearly understood from the foregoing description and drawings. Reaming blades 64 may be employed in the manner indicated if thought desirable, but ordinarily these will not be required, or will have very little duty to perform, on account of the ease with which the gauge of the drill hole may be maintained by advancing the cutting 25 blades.

I wish to call particular attention to the fact that, although the circulating water passes through my device from end to end, it is contained in a tightly closed course throughout, and is nowhere permitted to come into contact with any of the working parts. The power blocks may be packed by felt strips where they move into and out of the tubular housing, and the latter may be packed with heavy grease as a further insurance of keeping out mud and water. The more delicate of the working parts are tightly enclosed in the power blocks and body halves respectively, and may be constantly immersed in heavy oil or grease introduced through suitable plug holes for that purpose.

I claim as my invention:

1. A drilling bit having cutting blades adapted for being advanced obliquely to its axis and means adapted for actuation by frictional engagement with the walls of a drill hole for making said advancement.

2. A drilling bit having cutting blades adapted for being advanced obliquely to its axis and means comprising a feed nut for making said advancement; said means being operative through frictional engagement with the walls of a drill hole.

55 3. A drilling bit having cutting blades adapted for being advanced obliquely to its axis and means comprising a non-rotatable feed screw with a rotatable nut thereon for making said advancement; said means being operative through frictional engagement with the walls of a drill hole.

4. A drilling bit having cutting blades adapted for being advanced obliquely to its axis and means comprising a non-rotatable feed screw with a rotatable nut thereon for

making said advancement; said means being operative through frictional engagement with the walls of a drill hole and controlled by plunger rods normally projecting from the end of said bit.

5. A drilling bit having cutting blades adapted for being advanced obliquely to its axis and means comprising a rotatable feed nut for making said advancement; said means being operative through frictional engagement with the walls of a drill hole and adapted for automatic disengagement from said nut when the latter has made a pre-determined number of revolutions.

6. A drilling bit having cutting blades adapted for being advanced obliquely to its axis and means comprising a rotatable feed nut for making said advancement; said means being operative through frictional engagement with the walls of a drill hole and adapted for automatic disengagement from said nut when the latter has made a pre-determined number of revolutions; said bit having slidable plunger rods normally projecting from its end whereby said means can be controlled.

7. In combination with a drilling bit having cutting blades adapted for advancement obliquely to its axis; a rotatable feed nut adapted for causing said advancement; and disengageable means operative through frictional engagement with the walls of a drill hole for rotating said nut.

8. In combination with a drilling bit having cutting blades adapted for advancement obliquely to its axis; a rotatable feed nut adapted for causing said advancement; and disengageable means operative through frictional engagement with the walls of a drill hole for rotating said nut a pre-determined number of revolutions.

9. In combination with a drilling bit having cutting blades adapted for advancement obliquely to its axis; a rotatable feed nut adapted for causing said advancement; and means operative through frictional engagement with the walls of a drill hole for rotating said nut and automatically disengaging therefrom when said nut has made a pre-determined number of revolutions.

10. In combination with a drilling bit having cutting blades adapted for advancement obliquely to its axis; a rotatable feed nut adapted for causing said advancement; and means for rotating said nut a pre-determined number of revolutions comprising driving rolls adapted for frictional engagement with the walls of a drill hole disengageably connected with said nut.

11. In combination with a drilling bit having cutting blades adapted for advancement obliquely to its axis; a rotatable feed nut adapted for causing said advancement diametrically opposed power blocks adapted for mutual reaction through interposed com

- pression springs and having rollers adapted for frictional engagement with the walls of a drill hole; and flexible means for delivering power from said rollers to said nut.
12. In combination with a drilling bit having cutting blades adapted for advancement obliquely to its axis: a rotatable feed nut adapted for causing said advancement; diametrically opposed power blocks having interposed compression springs and rollers adapted for frictional engagement with the walls of a drill hole; and flexible means for delivering power from said rollers to said nut; said means being automatically disengageable from said nut when the latter has 15 made a pre-determined number of revolutions and adapted for being controlled by plunger rods normally projecting from the end of said bit.

GEORGE B. LOUDERBACK.
